WALTER F. BURGESS, OF ATWOOD, WEST VIRGINIA.

PLUG FOR GAS-WELLS.

No. 901,874.

Specification of Letters Patent.

Patented Oct. 20, 1908.

Application filed April 10, 1908. Serial No. 426,339.

To all whom it may concern:

Be it known that I, WALTER F. BURGESS, a citizen of the United States, and residing at Atwood, in the county of Tyler and State of West Virginia, have invented an Improvement in Plugs for Gas-Wells, of which the following is a specification.

My invention is an improved means for plugging gas wells, more particularly those whose yield of gas has ceased wholly or for the most part, and have been abandoned in consequence.

The invention includes a hollow tapered body portion, devices which are slidable thereon and adapted for wedging and locking the body in the well, and an elastic expansible sleeve or cylinder, and a tapered plug which is slidable in the body and thus adapted for expanding the sleeve.

The invention also includes other features of construction and combination of parts as will be hereinafter described.

In the accompanying drawings Figure 1 is an exterior view of the entire plug, the movable parts being shown in the normal position. Fig. 2 is a longitudinal section of the plug as shown in Fig. 1. Fig. 3 is a side view illustrating the position of the movable parts when the plug has been inserted in a well and locked and expanded therein. Fig. 4 is a longitudinal section showing the plug as it appears in Fig. 3, save that the rod which is normally connected with the expanding device has been withdrawn. Fig. 5 is a side view of the lower portion of such rod.

1 and 1^a indicate the two ends of the body of the plug, whose shanks are tapered toward each other and connected by central sleeve 40 coupling 2. These parts constitute the body of the plug. A soft-rubber sleeve or cylinder 3 is applied to the reduced lower end of the body portion 1^a and forms practically a continuation of the same. It can be expanded as shown in Figs. 3 and 4, by means of a tapered plug 5 which is connected by a breakable joint 5^a with a rod 6 which is slid- 45 able in the body portion 1, 1^a, 2, and connected at its upper end with a head 8 which in practice is suitably connected with the bailer (not shown). As a means for wedging and locking the body of the plug in the well, I employ devices which will now be described. One of such devices is applied to the upper tapered portion 1 of the body and the other to the corresponding lower tapered

portion 1^a. Each of said devices is formed of wedges 9 having spring shanks 10 by which they are connected with a ring 11. The said ring encircles the cylindrical shank of each 60 of the body parts 1 and 1^a, and the wedges 9 are curved in cross section and tapered outward corresponding to the cylindrical and tapered form of the shanks of the said parts 1, 1^a.

Between the coupling 2 and the ring 11 of the upper wedging and locking device is arranged a spiral spring 12, which is normally held compressed by means of a breakable wooden, or other, cross-pin 13. Said pin (as 70 shown in Fig. 2) passes through the tapered part of the shank 1^a and also through a slot 6^a in the rod 6 (see Figs. 2, 5), and its ends project over the top edge of the ring 11. It is apparent that if this pin be broken, the expansion of the spring 12 will automatically force the wedging and locking device upward as shown in Figs. 3 and 4, and thereby 75 lock the entire plug against downward movement so that it cannot go down the well 80 when the water is let in. The cross pin 13 is broken by upward traction applied to the rod 6. It is further apparent that if the lower locking device be slid into the position shown in Figs. 3 and 4, the device will be 85 similarly locked against upward movement in the well.

In practical use of my invention, the plug with its movable parts in the position indicated in Figs. 1 and 2, is lowered into the 90 well to the desired depth, and then, pulling up on the rod 6 by means of the bailer, the lower wedging and locking devices will slide downward by reason of friction with the surrounding part and thus be forced outward 95 on the lower tapered body 1^a (as shown in Figs. 3 and 4), and this obviously locks the plug against upward movement. Then the bailer connection slips past a set-screw 14 (see Fig. 1), and the hollow slidable plug 5 at the lower end of part 1^a is drawn upward and expands the rubber sleeve 3 so that it closes tightly against the surrounding part, as indicated in Figs. 3 and 4. This effectually closes the well against the escape of gas, and the pressure of the latter forces the expanding plug 5 still further upward, thus tightening the plug more effectually. The pull by means of the bailer, being then continued, or rather the bailer being "jarred up", the breakable pin which forms the joint 5^a between the expanding plug 5 and

the rod 6 is broken or cut off, and the rod 6 sliding further upward, breaks the cross-pin 13 so that the upper wedging and locking device is released and instantly forced upward by the spring 12 into the locking position in Figs. 3, 4. Thus, if the gas pressure below the plug exceeds the water pressure above it, or the water pressure exceeds the gas pressure, the plug holds equally well in either direction. In practice, the next step consists in running thin cement down the hole so as to fill up the passage in the body of the plug, or in the parts 1 and 1^a, and all space around outside of body of plug. After such cement has had time to set, the well casing is pulled and the water let in, which completes the entire operation.

What I claim is:

1. The improved gas-well plug comprising a hollow body having tapered portions, slideable wedging and locking devices applied to such tapered portions, a spring acting against one of said devices for forcing it along the adjacent tapered portion, a breakable pin traversing the body of one of the tapered portions and serving to hold one of the locking devices in retracted position, a rubber sleeve applied to the lower portion of the body, an expanding plug operatively connected with said sleeve, and a rod having a breakable-joint connection with such expanding plug and adapted to slide in the

body of the gas-plug, substantially as described.

2. The improved gas-well plug comprising upper and lower tapered portions, a rubber sleeve applied to the lower end of the plug, and a slideable plug adapted to expand said sleeve, a rod connected with such plug and adapted to slide in the body of the gas-plug as a whole, and locking devices which are movable on the body of the gas-plug for preventing upward or downward movement of the same in the well, substantially as described.

3. In a gas-well plug, the combination with the tapered body of the same, of a locking device comprising a wedge and a part securing the wedge slidably on the tapered portion, a spring tending to force the locking device outward, a breakable cross-pin holding the device in retracted position against the tension of said spring, and a slotted rod which is slideable in the body of the plug and having a shoulder adapted to engage the breakable pin, whereby, when traction is applied to the rod, the pin may be broken and the locking device released in the manner described.
